UNITED STATES PATENT OFFICE.

ISRAEL LUDLOW, OF NEW YORK, N. Y.

SUBMERSIBLE GUN-MOUNT.

1,309,483.

Specification of Letters Patent.

Patented July 8, 1919.

Application filed June 28, 1917. Serial No. 177,480.

To all whom it may concern:

Be it known that I, ISRAEL LUDLOW, a citizen of the United States, and a resident of the city of New York, borough of Manhattan, in the county and State of New York, have invented a new and Improved Submersible Gun-Mount, of which the following is a full, clear, and exact description.

Among the principal objects which the present invention has in view are: to provide ordnances disposable in the open sea and visible only at the moment of discharge; to provide submersible mounts for heavy ordnance of the desired type; to provide means for mounting ordnance in swinging submersible mounts so arranged that the ordnance is above the surface of the medium in which the mount is submerged at the moment of discharge, and settles below the said surface after and as the result of said discharge; to provide means for pointing the ordnance mechanically; to provide means for sighting the target or a signal station from a submerged operating station; and to provide portable submersible mounts for ordnance with water covered means for receiving the ordnance on its recoil after discharge.

Drawings.

Figure 1 is a side view of a gun mount constructed and arranged in accordance with the present invention, the same being shown in conjunction with a gun carried thereby, said gun being shown by full lines as in firing position, and by dotted lines as in submerged position;

Fig. 2 is a cross section taken as on the line 2-2 in Fig. 1;

Fig. 3 is a section showing a modified form of the invention;

Fig. 4 is a vertical cross section showing a modified form of the invention;

Fig. 5 is a detail view of a fragment of the forward end of the gun, showing the mechanism for operating the closure cap for the gun.

Description.

As seen in the drawings, a submersible vessel 8 having a periscope 9 and conning tower 10, is also provided with a gun chamber 11. The vessel 8 is constructed on lines and design to afford strength and room in the gun chamber 11 calculated to meet the requirements for the handling of heavy ord-

nance, such as indicated by the recoil gun 12 shown in the drawings. The gun 12 is preferably constructed on the lines of the disappearing gun used in land fortifications. The conventional recoil cushion cylinders 13 are provided, as well as the swinging arms 14 and 15. The arms 14 and 15, as shown best by the dotted lines in Fig. 1 of the drawings, are so disposed that when the gun 12 recoils, the arms 14 and 15 are folded to assume positions relative to the gun, in which positions both of the arms and the gun are depressed ready to be stowed or housed in the chamber 11.

In active position, the hull of the vessel 8 is submerged to the top of the conning tower 10. If greater submersion is desired, the arms 14 and 15 are made of greater length so that when the gun is discharged, it is raised above the surface of the water.

The arms 14 and 15 are directly mounted on a turntable 16. The turntable 16 is provided with the usual gear members adjacent the periphery thereof, said members being in the present instance, engaged by a suitable pinion 17 extended from and to be driven by an electric motor 18. Sufficient control of the turntable 16 is obtained to point the gun irrespective of the direction of the keel of the vessel 8. The immediate control of the gun-pointing mechanism may be assigned to the officer in the conning tower or his assistant.

The chamber 11 opens through the deck 90 of the vessel 8 when the doors or hatches 19 are lifted. The hatches 19 are provided with sealing gaskets so that when closed, the chamber 11 is watertight.

The chamber 11 is provided with the usual 95 inlet and outlet pipes 20 and 21. The pipe 21 is suitably connected with a pump, the operation whereof serves to eject the water which is contained in the chamber 11 after the operation of the gun and the closure of 100 the hatches 19. This pump may be of any suitable construction. Both pipes 20 and 21 have valves 22 whereby the pipes may be manipulated to facilitate the operation for which the said pipes are designed.

As seen best in Figs. 1 and 2 of the drawings, the gun barrel is provided for direct contact with water by means of a casing 23. The casing 23 has a breech cap 24, which is removed when loading the gun, and to gain 110 access to the breech-block mechanism thereof. The casing 23 is constructed of any

suitable material and provides an air space between the gun and the casing. This air space under the normal conditions of service provides for insulating the gun from 5 the water into which it plunges after being discharged. The possibility or danger of cracking the gun by too rapid cooling of the barrel is thereby avoided.

In Fig. 3 of the drawings, a modified 10 form of casing or cover for preventing the barrel of the gun 12 coming in contact with the water, is shown. The modification consists in an open cap or cover 25, the ends whereof are closed to provide an air trap or 15 pocket in the upper regions of the cap or cover. Within these regions, the gun is held. The muzzle of the gun is closed when inactive by a plug cap 26. A small electric motor 27 or other suitable device operates 20 to close the cap 26 over the muzzle. Provision is made so that the operation of the motor 27 shall completely close the muzzle opening to the bore of the gun prior to the immersion of the same within the water. 25 With gun mounts thus constructed, provision is made for extending harbor or coast defense beyond the usual limits of ordinary gun fire. A system of fortification for coast is provided which is mobile, being adapted 30 for rapidly moving from point to point. Also the location of the units constituting the fort is baffling, the periscope of the submersible vessel only being visible during periods of loading or between the periods of 35 firing.

When the vessel 8 is provided with means of propulsion, the points at which the gun may be presented for firing can be indefinitely varied.

40 In Fig. 4 of the drawings, a modified form of the invention is shown, the modification consisting in providing a full-sized inverted turret 28, and means for elevating and lowering the same for housing in narrow upper turned channels formed by the spaced tubular walls 29 and 30. Extending through the lower edge of the walls 29 and 30 are rack bars 31, the teeth whereof are engaged by pinions 32 of electric motors 33. When 45 the motors 33 are energized, the rack bars 31 and turret 28 supported thereby are elevated or depressed in accordance with the operation of the said motors.

50 Mounted within the tubular wall 30, is 55 the turntable 16. The turntable 16 when applied to this form of the invention, has a gasket 34, which seals or holds watertight, the joint between the inner wall 30 and the edge of the turntable. The gasket 34 serves 60 to prevent the ingress of water to the hull of the vessel 8 when the turret 28 is lifted above the water in which the vessel is submerged.

Suspended from the turntable 16 is the 65 tubular runway 35. The runway 35 has a

ladder 36, by which the gun crew can pass from the hull of the vessel to the interior of the turret 28. The runway 35 is sealed and made watertight by a door 37, which covers the upper end of the runway. The door 37 70 and the upper end of the runway 35 extend above a working platform 38, which is supported by lattice work 39 above the turntable 16.

The turntable 16 is preferably cylindrical. 75 The elongated chamber 40 is extended above the main body of the turret to form a housing for the gun 12 when the same is in the recoil position.

The modification shown in Fig. 4 and just 80 above described, provides for the expulsion of water from the gun chamber after the same has been fired and has recoiled to the submerged position.

The air which is trapped in the turret 28 85 is sufficiently compressed by the water seal to drive from the chamber all water trapped therein. To this end, a pipe 41 is connected with the mounting of the turn table 16 and in open communication with an exit port 90 42 formed therein. The pipe 41 extends through the deck of the vessel 8 through the water surrounding the same.

When provided with a turret 28, the operation is as follows: Preliminary to firing 95 the gun, the motors 33 are energized to lift the turret to a position where the lower edge thereof is above the firing position of the gun, as shown by dotted lines in Fig. 4. The elevating mechanism of the gun is immediately operated, and the gun is lifted above the surface of the surrounding water. The gun is fired and recoiled to its submerged position. The motors 33 are immediately 100 actuated to lower the turret 28. When the lower edge of the turret enters the water, it is obvious that the air contained in the 105 turret is trapped therein.

When the lower edge of the turret 28 110 enters between the walls 29 and 30, the compression of the trapped air immediately operates upon the entrapped water and forces the same through the pipe 41 outward to the surrounding water in which the vessel 8 is 115 submerged.

The fitting between the wall of the turret 28 and the wall 30, is sufficiently free to permit the water which has entered the space between the walls 29 and 30 when the turret was raised, to escape from the said space 120 to be expelled by way of the pipe 41 from the inside of the casing.

When the turret is fully seated, the compression of air is sufficient to practically exclude all of the water which was trapped by the turret. A check valve or cover 43 at the outer end of the pipe 41 serves to prevent the flow of water backward through the pipe 41.

The door 37 is opened immediately after 130

the turret 28 has settled to its closed position, the compressed air in the turret entering the body of the vessel 8 through the runway 35 when the air pressure within the 5 hull of the vessel and the turret 28 is equalized. The gun crew are at liberty to enter the turret for loading the gun 12. When the gun 12 is loaded, the men pass through the runway 35, closing the door 37. The 10 motors 33 are then actuated to elevate the turret. It will be understood that when the turret is being elevated, the door 37 will lift to prevent any rarefaction of the air within the turret, which might retard its 15 elevation or overload the motors 33. The lift of the door 37, however, is not sufficient to permit the ingress of water the moment the lower edge of the turret passes above the edge of the wall 29.

20 The mechanism for raising the gun 12 may be of any approved type, that shown in the drawings employing an electric motor 44, the armature shaft of which has a pinion 45 engaging a large gear wheel 46, 25 which is attached to the arm 14 of the gun supports. When employing such a lifting mechanism, the fighting officer in the conning tower 10 of the vessel, after the turret 28 has been elevated, has the current supplied 30 to the motor 44, which operates to rotate the wheel 46 to raise the gun to the position shown in Fig. 1 of the drawings. The recoil of the gun operates to return the same to the crouching position as shown in dotted 35 lines in Fig. 1 of the drawings. As the gun settles back to the crouching position, the cap 26 is closed over the muzzle of the gun 12. This is accomplished by means of a small electric motor 27, the armature shaft 40 of which has a pinion 47, the teeth whereof are engaged by the teeth of a quadrant 48 attached to the cap 26. The electric current for which the motor 27 is operated, is controlled by a switch located within the vessel. 45 This switch is closed at the same time that the circuit having the wire 49 for igniting the charge within the gun is closed.

It is found that the greater rapidity of

the discharge of the gun permits the ejection of the projectile and the gases from the 50 gun prior to the closing of the cap 26. The cap 26 is, however, closed before the gun is immersed in the surrounding water.

Claims.

55

1. A gun mount having means for elevating the gun for discharge and for depressing the same during the recoil of said gun; a portable submerged support for said gun; and means for pointing said gun, said means 60 embodying a periscope, and mechanical devices for shifting the gun while the base thereof is immersed in water.

2. A gun mount having means for elevating the gun for discharge and for depressing 65 the gun during the recoil of said gun; a portable submerged support for said gun; means for inclosing said gun in its recoil position for forming a water-tight chamber surrounding the same; means for ejecting 70 water from said chamber; and means for protecting the gun against rapid radiation of heat thereof.

3. A gun mount having means for elevating the gun for discharge and for depressing 75 the gun during the recoil of said gun; a portable submerged support for said gun; means for inclosing said gun in its recoil position for forming a water-tight chamber surrounding the same; means for ejecting 80 water from said chamber; and means for protecting the gun against rapid radiation of heat thereof, said means embodying an air jacket enveloping said gun.

4. A gun mount having means for elevat- 85 ing the gun for discharge and for depressing the same during the recoil of said gun; a portable submerged support for said gun; means for inclosing said gun in its recoil position for forming a water-tight chamber 90 surrounding the same; and means for ejecting water from said chamber, said means embodying a continuous-wall turret, and means for compressing air within said tur- ret for the expulsion of water therefrom.
